UNITED STATES PATENT OFFICE.

GUS MAJOR KAISER AND CLARENCE ADLER, OF NEW YORK, N. Y.

CHAIR.

1,286,338.

Specification of Letters Patent.

Patented Dec. 3, 1918.

Application filed May 8, 1916. Serial No. 96,001.

To all whom it may concern:

Be it known that we, GUS MAJOR KAISER and CLARENCE ADLER, both citizens of the United States, residing in the borough of

5 Manhattan, city, county, and State of New York, have invented certain new and useful Improvements in Chairs, of which the following is a full, clear, and concise description.

10 The present invention relates generally to improvements in chairs and is more particularly directed to the provision of a chair, wherein the seat is adjustable to accommodate persons of different stature, my invention thereby being especially adaptable to the requirements of pianists, organists and other musicians, typists, clerks and other office employees.

20 The primary object of this invention is to provide a chair of the type heretofore referred to, which will be absolutely rigid in construction and will have an adjustable seat, which may be instantly raised or lowered to any desired position by a single operation.

25 A further object of the present invention is to produce a chair of the character set forth which may be economically produced and will have but few operating parts so 30 constructed and arranged as to provide a structure wherein the necessity for adjustments and repairs will be obviated and a highly durable and efficient device produced.

Our invention also comprehends means 35 for automatically locking the seat in any desired position, which means are capable of manual operation to unlock the seat for movement in an upward or downward direction.

40 Other objects and advantages of the employment of our invention will become apparent as the description proceeds and we would have it distinctly understood that we have illustrated but one embodiment of our 45 invention to render a clear and comprehensive understanding thereof and that we desire to secure for ourselves all of the equivalents of the structure shown, both in uses and arrangements of parts, and details of 50 operation, to which we may be entitled under our invention in its broadest aspect.

We shall now proceed to describe our invention with reference to the accompanying drawings and then point out with more particularity the essential elements of novelty 55 therein in the appended claim.

In the drawings,

Figure 1 is a view in perspective of a chair made in accordance with our invention.

60

Fig. 2 is an under-plan view of the seat and portions of the operating mechanism.

Fig. 3 is a transverse sectional view on the lines A—A of Fig. 2.

Fig. 4 is an enlarged detail of our improved locking means, and

Fig. 5 is an enlarged fragmentary detail view, showing the method of attaching the supporting standard to the chair seat.

Referring now to the drawings in detail, 70 in which like characters of reference are employed to designate similar parts throughout the several views, 7 represents the chair frame having the upright back 8, the side rungs 9 and cross-rungs 10 and 11 fastened to and reinforcing the legs 12 in the well-known manner.

The seat 16 of the chair may be of any desired shape, such, for instance, as shown in Figs. 1 and 2, and is supported preferably by four spirally threaded standards or high pitch screws 20, the forward pair of which are housed or inclosed in the front legs of the chair, as shown in Figs. 1 and 3, each of the legs being provided with a thimble 14^a which is seated in a bore therein. The rear standards or supports 20 are contained within the preferably cylindrical housings 14, which may be made of metal, wood or any other suitable material and extend from the frame 7 of the chair to the adjacent side rungs 9 thereof, the lower ends of these housings being held in fixed or rigid engagement with the rungs by means of the clamping plates or members 9^a. It is obvious that other methods may be employed in fastening the housings to the chair rungs and the chair frame and that the forward pair of standards in lieu of being housed within the front legs of the chair may be contained or inclosed within housings similar to those indicated at 14, positioned behind the front legs of the chair.

100 Adjacent to each corner of the seat 16, we secure to the under-surface thereof, by means of screws or the like 18, a plate 17 apertured at 17^a to form a bearing for the pin 20^b, the contiguous portion of the seat being recessed for the reception of the head 20^a of said pin. (See Fig. 5).

110 As will be observed, the upper end of each of the standards or supports 20 is contracted

to form a shoulder on which is mounted a sprocket wheel 21, this sprocket wheel being keyed to the standard by means of a transversely extending pin 20^a which passes 5 through both the sprocket and the shoulder of the support and also through the shank of the pin 20^b seated within the central bore provided in the shoulder, said sprocket, support and the pin 20^b being thereby rigidly locked together and rendered capable 10 of movement as an integral piece.

The teeth of the sprocket 21 are adapted to register or mesh with the links in a continuous chain 22, this chain, as will be apparent from Fig. 2 of the drawings, passing through the rectangular guideways 25^a positioned at each side of the seat and around all four sprocket wheels, being rendered invisible by the downwardly projecting flange 23 forming a part of the seat 16 (see Figs. 1 and 3).

It will be manifest from the description of our invention thus far given, that upon a person grasping the sides of the seat 16 and exerting an upward pull thereon the standards or supports 20 will be caused to rotate by the meshing of the spiral threads thereon with the complementary threads on the inner wall of the fixed sockets 24, communicating with the upper ends of the housings 14 and 14^a (see Fig. 3) the revolution of the standards being positively timed or synchronized by the chain 22 traveling on the respective sprockets 21. This arrangement not only insures the raising of the seat in a true horizontal plane, but also prevents jamming of the standards in their sockets and results in an equal distribution of the power applied to the raising or lowering 40 of the seat, so that a force applied to any portion of the seat will cause synchronous rotation of the high pitch screws.

When the seat is in the desired position, it is obvious that means must be provided 45 to lock it therein and for this purpose, we have found it expedient to form a locking means consisting of a plate 25 formed of metal or any other suitable material, having a downwardly extending grip or handle 50 26. This plate 25 is mounted to slide within a slot formed by recesses in each of the side flanges 23, coöoperating with the underside of the seat 16, as clearly shown in Fig. 3, and carries at its inner end a downwardly extending 55 enlarged portion 27 provided with

a plurality of preferably cylindrical pins 28. Extending from the opposite side of the pin bearing portion 27 of the plate 25 is a guide rod 29 having a bearing in the eyelet 30 screwed home in the underside of the seat 16 (see Fig. 3). A spring 31 is mounted upon this guide rod 29, one end of the spring bearing against the eyelet 30, the other end thereof abutting against the portion 27 of the plate 25.

With this construction, it will be clearly apparent that the tension of the spring 31 will normally be exerted to force the plate in a direction outwardly relatively to the chair, so that the pin 28 on the enlarged portion 27 will enter the contiguous links 22^a of the chain 22, as shown in Fig. 2, thus positively locking the chain against movement and thereby preventing the further revolution of the standards or supports 20. 75 To adjust the seat, the pins 28 are disengaged from the links by pressing the plate 25, through the medium of the handle or grip 26, inwardly relatively to the seat of the chair against the tension of the spring 80 31. This releases the chain held in the guideway 25^a and the seat may then be raised or lowered in the manner heretofore described. When the desired position has been secured the plates are released and the pins 28 engage the links 22^a.

While we have described our invention with particular reference to its application to a chair, which is especially suitable to the requirement of musicians and others, it will 90 be seen that our invention is susceptible to incorporation in tables, surgical chairs, beds, cots and various articles of utility wherein it is desired to render one portion thereof adjustable relatively to another.

Having thus described our invention what we claim as new and desire to secure by Letters Patent is:

In combination with a chair frame, a seat, a plurality of high pitch screws carried by 100 said seat and coöoperating elements on said frame, sprocket wheels on said screws, a synchronizing chain coöperating with said sprocket wheels, and locking means engaging said chain, whereby upon release of the 105 locking means a force applied to any portion of the seat will cause synchronous rotation of said screws.

GUS MAJOR KAISER.
CLARENCE ADLER.
